UNITED STATES PATENT OFFICE.

JOSEPH WHITAKER, OF WOONSOCKET, AND OLNEY L. SMITH, OF PROVIDENCE, ASSIGNORS TO SIMEON S. COOK, OF WOONSOCKET, R. I.

IMPROVEMENT IN CAR-AXLE BOXES.

Specification forming part of Letters Patent No. 147,723, dated February 17, 1874; application filed January 24, 1874.

To all whom it may concern:

Be it known that we, JOSEPH WHITAKER, of Woonsocket, in the county of Providence and State of Rhode Island, and OLNEY L. SMITH, of Providence, in the county of Providence and State of Rhode Island, have invented a new and useful Improvement in Lubricators for Car-Axes; and we do hereby declare the following to be a full and exact description of the same, reference being had to the accompanying drawings forming part of this specification, in which—

Figure 1 is a longitudinal vertical section of a housing or car-axle box, and the car-axle with our improved lubricator applied thereto. Fig. 2 is a transverse section of the same.

Similar letters of reference in the accompanying drawings denote the same parts.

Our invention relates, first, to an improvement in car-axle boxes; and consists in the employment of a circular flange surrounding the perforation for the journal in the outer end of the box or housing, for the purpose of keeping out dust from the box, an inner perforated partition, parallel to the end of the box, being employed, having an aperture, preferably near its bottom, for the passage of oil thrown off the journal back into the oil-reservoir, as hereinafter more fully set forth. Our invention further consists in the employment of a collar to prevent the escape of oil, situated in the passage between the partition and the outer end of the box, the said collar being provided with a suitable packing. Our invention also consists in the employment of a dust-collar on the axle, having a suitable packing.

In the accompanying drawings, A is the car-axle box or housing, having a lug or projection, B, on the under surface of the top, which fits into a groove in the block C, which bears upon the axle D of the car. E is a roller journaled in the frame F, carrying the spring-frame G, carrying the roller E, is placed in the oil and carrying it to the journal D. G is a partition near the outer end of the box, provided with a perforation, a, for the passage of the axle or journal D, and an aperture, a', preferably near

the bottom, for the return of any oil in the passage P back into the oil-reservoir R.

It will be seen that, by the employment of the partition G, a passage, P, open at the top, is formed between said partition and the end of the box, and any oil thrown off the journal will pass into the passage, being prevented from passing out of the box by the end piece H of the latter.

The aperture a' may be formed by so constructing the partition that it will not extend to the bottom of the box, or a vertical or inclined slot may be made in the partition, the nature of my invention requiring communication between the passage P and the oil-receptacle for the return of oil to the reservoir. I is a circular flange surrounding the perforation for the journal in the end of the box, to protect the journal-perforation from dust, in connection with a dust-collar, which will presently be described. K is a collar, provided with a fibrous or other suitable oil-tight compressible packing, b, which surrounds the journal D, and is situated in the passage P. The collar K is preferably dished, with the dish toward the interior of the box, though we do not limit ourselves to that form of collar, as other forms may be advantageously employed.

In the operation of the lubricator, the oil is carried by the roller E to the car-axle D, and is thence carried along the axle to the collar K, and, being prevented by the compressible oil-tight packing b from passing farther along the axle, is thrown down by the collar K into the passage P, from which it passes through the aperture a' into the oil-chamber. L is a collar to prevent the ingress of dust. It surrounds the axle, and is preferably made of a dish form, as shown in the drawings, though we do not confine ourselves to that precise form of collar. b' is a packing between the collar L and the journal of fibrous or other suitable compressible dust-tight packing.

It will be seen, by my construction, that no oil can escape from the axle-box and be wasted, and that all ingress of dust is prevented.

The dust and oil collars may be made in one or several pieces. The passage P is left open at its top for the insertion of the oil-collar K, and is afterward closed to prevent the ingress of dust.

We are aware that a collar having its interior circumference lined with an elastic compressible material forms the subject-matter of an application for a patent now in the office, and we, therefore, disclaim this as a part of our invention.

We claim as our invention—

1. The partition G, having an aperture a', in combination with the oil-collar K, circular

flange I, and dust-collar L, substantially as and for the purpose set forth.

2. The roller E, oil-reservoir R, and journal D, in combination with the partition G, oil-collar K, circular flange I, and dust-collar L, substantially as and for the purpose set forth.

JOSEPH WHITAKER.

OLNEY L. SMITH.
